LENS GRINDING MACHINE

Kenneth C. Burroughs, Rochester, N. Y., assignor
to Bausch & Lomb Optical Company, Rochester, N. Y., a corporation of New York

Application April 10, 1935, Serial No. 15,623

6 Claims. (Cl. 51—131)

The present invention relates to lens grinding and more particularly to an apparatus for grinding and polishing lenses or the like.

One of the objects of the present invention is to provide a new and improved apparatus for grinding and polishing lenses. Another object is to provide an automatic machine for grinding and polishing lenses. A further object is to provide a lens grinding machine having a plurality of abrading stations and means for moving the lens from station to station. Still another object is to provide an improved spindle assembly for an automatic lens grinding machine. A still further object is to provide an improved means for applying pressure to one spindle of a lens grinding machine. A further object is to provide an improved timing mechanism. These and other objects and advantages reside in certain novel features of construction, arrangement and combination of parts as will hereinafter be more fully set forth and pointed out in the appended claims.

Referring to the drawings:

- Fig. 1 is a diagrammatic rear view of a lens grinding machine embodying this invention.
25 Fig. 2 is a diagrammatic top view of same.
Fig. 3 is a side elevation of one of the abrading units.
30 Fig. 4 is a vertical section of an abrading tool spindle with parts shown in elevation.
Fig. 5 is a diagrammatic view of the timing mechanism.

One embodiment of this invention is illustrated in the drawings wherein 10 indicates a supporting table upon which are mounted a lens blocking device 11, a diamond grinder 12, an emery grinding station 13 and two polishing stations 14 and 15, for example. A rough molded or pressed lens blank 16 is placed in the machine where it is secured to a block 17 and passed through the successive grinding and polishing stages until it emerges finished on one side.

The lens blocking device 11, the structural details of which form no part of this invention, comprises any suitable device for securing the lens blank 16 to the block 17. A device which places a small amount of melted pitch on the block 17, presses the lens blank 16 into this melted pitch and then cools the pitch so as to fix the lens blank 16 rigidly to the block 17, would be satisfactory. 45 The cam 18, mounted on the shaft 19, and the follower 20, carried by the lens blocking device 11, could furnish the power for any necessary moving parts.

The structural details of the diamond grinder 50 12 likewise form no part of the present invention.

The grinding tool, which may be of diamond charged copper or the like, is driven at high speed by a motor 21. The lens 16 and block 17 are carried upon a rotatable and axially movable spindle which is rotated at a slower speed than the tool 5 by a belt 22 driven from a shaft 23. The axial movement of the spindle is controlled by the cam 24 on the shaft 19, and the follower 25.

The structural details of the emery grinding device 13 also form no part of the present invention. This device is described and claimed in the co-pending application of Carl E. Anderson, Serial No. 433,934, filed March 7, 1930, entitled "Method and means for abrading lenses", now Patent No. 2,105,175, dated Jan. 11, 1938. The 10 upper spindle of the emery grinder 13 is driven by the belt 26 from the shaft 23. The lower spindle is both rotatable and axially movable and is rotated by the belt 27 from the shaft 23. The lower spindle is moved axially toward and from 20 the upper spindle by the cam 28 on the shaft 19, and the follower 29.

The polishing units 14 and 15 are identical and each comprises a lower driven spindle 30 rotatably carried by a lever 31 which is pivoted at 32 to the 25 table 10. The spindle 30 has a pin 33 engaging a slot 34 in the block 17 for rotating the lens. A belt 35 serves to drive the spindle 30 continuously from the shaft 23. The lever 31 carries a follower 36 for engaging a cam 37 on the shaft 19. From 30 Fig. 3 it is apparent that when the shaft 19 is rotated the cam 37 will cause the lens 16 to move away from the abrading tool 38. This lower spindle assembly is substantially the same in the diamond grinder 12, the emery grinder 13 and the 35 two polishers 14 and 15.

The upper spindle assembly comprises a housing 39 secured to a shaft 40 which is rockably mounted upon the top of the table 10. Within the housing 39, a spindle 41 is slidably and rotatably journaled in bearings 42, and this spindle 41 detachably carries the abrading tool 38 at its lower end. A bracket 43 secured to the housing 39, carries at its upper end a cylinder 44 in which a piston 45 is slidable. A thrust bearing 46 connects the piston 45 to the spindle 41. To limit the downward movement of the spindle 41, an adjustable collar 47 is placed on the spindle 41 between the cylinder 44 and the housing 39. The upper spindles 41 of the polishing units 14 and 15 50 are not positively driven but receive their movement from the friction between the lens 16 and the tool 38.

In the case of the emery grinding unit 13 and the two polishing units 14 and 15, it is essential 55

that the abrading tool 38 be held against the lens 16 with a certain amount of pressure. The upper spindle 41 of each unit is free to slide longitudinally to accommodate different thicknesses of the lens 16 and block 17 and also to take up any wear in the tool 38. Thus when the lower spindle is raised by the action of its cam, the tool 38 and spindle 41 are moved upward by the lens 16. If, during this movement, the spindle 41 were pressed downward by the pressure necessary for grinding or polishing, the force between the two spindles would be sufficient to break the lens.

The desired pressure between the lens 16 and the tool 38 is obtained by admitting compressed air or other fluid to the cylinder 44. A reservoir 48 for the compressed air has an outlet 49 which connects to a valve mechanism 50. The valve mechanism 50 is controlled by a cam on the shaft 19 so that the air pressure is admitted to the cylinders 44 through the pipe 51 only when the spindle 30 is at, or near, the top of its travel.

The upper spindles 41 of the polishing units 14 and 15 are carried by the rockable shafts 40. These shafts 40 are driven with a slight oscillating movement from the shaft 23 by means of belts 54. Such a slight movement of the tool across the lens gives the polisher a more uniform polishing effect.

The abradant is supplied to the emery grinding unit 13 and the two polishing units 14 and 15 by means of automatic mechanisms 53 connected by belts 54 to a shaft 55 under the control of an independent motor 56. Compressed air is introduced into each mechanism 53 by an inlet pipe 57 connected to the outlet pipe 49. The structural details of these mechanisms form no part of the present invention but are described and claimed in the copending application of Kenneth C. Burroughs, Serial No. 8,673, filed February 28, 1935 entitled "Abradant supplying device", now Patent No. 2,083,773, dated June 15, 1937.

The lenses 16 and blocks 17 are moved from one station to the next by a plurality of forks 58 mounted upon a travelling bar 59. This bar 59 moves inward until each fork 58 grasps a lens 16 and block 17. The bar then moves outward, then moves to the left as seen in Fig. 2, then moves inward where the lens 16 and block 17 are removed. The bar 59 then moves outward and returns to its original position. The inward and outward movements of the bar 59 are controlled by the reversible cylinder and piston mechanisms 60 and the lateral movement of the bar 59 is controlled by the reversible cylinder and piston mechanism 61. These cylinder and piston mechanisms are operated by pressure from the reservoir 48 and controlled by valves 62, 63, 64 and 65 which are operated from the shaft 19.

When the movement of the lenses from one station to the next is to take place, the valve 65 is opened admitting compressed air through the pipes 66 to the front end of each cylinders 60 thus moving the bar 59 inward. The valve 62 is then opened admitting compressed air to the other end of the cylinders 60 through the pipes 67 moving the bar 59 outward. Valve 64 then admits the compressed air through the pipe 68 to the right hand end of the cylinder 61 as seen in Fig. 2 moving the bar 59 to the left as seen in Fig. 2. Valves 65 and 62 operate as before and then valve 63 opens admitting air to the left hand end of the cylinder 61 through the pipe 69 returning the bar 59 to its original position. The movement of the bar 59 and forks 58, as well as the movement of the lower spindles of the abrad-

ing units are all controlled from the shaft 19. The bar 59 and forks 58 move inward and grasp the lens blocks 17 before the lower spindles move downward. As can be seen in Fig. 3, the fork 58 holds the lens 16 and block 17 in the same plane while the spindle 30 moves away from the block 17. When the lens 16 and block 17 are to be left at the next unit, the spindle 30 rises and grips the block 17 and then the fork 58 is withdrawn.

The main drive shaft 23 is driven by a motor 70 which also drives a belt 71 connected to a pulley 72 on the timing mechanism 73. This timing mechanism 73, which is diagrammatically shown in Fig. 5, intermittently drives the control shaft 19 for periodically actuating the cams 18, 24, 28 and 37 and valves 50, 62, 63, 64 and 65 in proper timed relation. The pulley 72 is mounted upon a shaft 74 and drives the shaft 19 through the pulley 75, chain 76, pulley 77, clutch 78, worm 79 and gear 80. The pulley 72 is continuously driven and the intermittent movement on the shaft 19 is obtained by connecting and disconnecting the clutch 78.

The clutch 78 is actuated by a bell crank lever 81, one end of which is connected to the reversible cylinder and piston mechanism 82. Compressed air is admitted to the timing mechanism by a pipe 83 connected to the pipe 49 and from this pipe 83 two branches 84 and 85 lead to the two ends of the reversible cylinder and piston mechanism 82. In the pipe 84, a valve 86 opens to permit the air to enter one side of the cylinder and piston mechanism 82 and move the lever 81 to close the clutch 78 and thus complete the drive from the pulley 72 to the gear 80 and shaft 19.

Mounted upon the shaft 74 is a worm 87 which drives a cam 88 through gears 89, 90, 91 and 92. A lever 93, pivoted at 94 is urged away from the valve 86 by a spring 95. Once in each revolution, the cam 88 engages the lever 93 and moves it to open the valve 86 admitting air to the cylinder and piston mechanism 82 to close the clutch 78. As soon as the cam 88 releases the lever 93, the lever 93 is returned to its normal position by the spring 95. In this position the lever 93 opens an exhaust valve 96 which releases the air pressure in the cylinder and piston mechanism 82. The bell crank lever 81, however, remains in its position with the clutch 78 closed.

The pipe 85 leading to the other end of the cylinder and piston mechanism 82 is controlled by a spring valve 97. This valve 97 is such that in its normal position the pressure line is closed and any pressure in the cylinder and piston mechanism 82 is released. Upon pressing of the stem 98 the pipe 85 is opened admitting compressed air to the cylinder and piston mechanism 82 which serves to open the clutch 78. As soon as the stem 98 is released, it is returned to its original position by a spring, not shown. The bell crank lever 81 remains in its position and the clutch 78 remains open.

It is essential that the shaft 19 always be stopped in exactly the same position and this stopping is accomplished by pressing the valve 65 stem 98. A hammer 99 is pivoted at 100 on the gear 80 and is urged in the direction of rotation of the gear 80 by a spring 101. The hammer 99 has a notch 102 which is adapted to be engaged by a trigger 103 pivoted at 104 to the gear 80. A fixed cam surface 105 adjacent the valve 97 serves to hold the hammer 99 during the rotation of the gear 80 so that the trigger 103 is engaged in the notch 102 holding the hammer 99 against the tension of the spring 101. As the gear 80 revolves, 75

a projection 106 on the trigger 103 is engaged by a fixed release member 107 which releases the trigger 103 from the notch 102 permitting the spring 101 to move the hammer 99 to strike the valve stem 98 thus opening the clutch.

5 The worm 81 and gears 89, 90, 91 and 92 give a very great reduction of motion between the shaft 14 and the cam 88. Thus the shaft 14 will rotate a large number of times for each actuation 10 of the valve 86 with its engaging of the clutch 78. The motion reduction between the shaft 14 and the shaft 19 is relatively small. In this way, a long abrading time is had while the shaft 19 is still and the transition period is kept small by rotating the control shaft 19 at a good rate when it 15 is actuated.

In operation, the motor 70 drives the main shaft 23 from which the spindles of the abrading units are driven and also drives the control shaft 20 19 through the timing mechanism 73. When the shaft 19 begins to turn, the pressure on the upper spindles of the abrading units is released and the bar 59 moved inward to grip the lens blocks 17. The cams 24, 28 and 37 then move the driven 25 lower spindles and the lens blocks 17 are withdrawn and moved to the next abrading unit. The driven lower spindles are then raised, the bar 59 returned to its original position and the valve 50 actuated to renew the pressure on the 30 upper spindles.

From the foregoing it will be apparent that I am able to attain the objects of my invention and provide a new and improved machine for automatically grinding and polishing lenses. 35 Although the parts combine to form a new machine and interact to form a true combination, the separate mechanisms can be used with advantage in other machines. For example, the separate abrading units and the timing mechanism 40 could be used in other machines. Various modifications can, of course, be made without departing from the spirit of this invention or the scope of the appended claims.

I claim:

- 45 1. An abrading apparatus comprising a work support, a spindle support in opposed relation to said work support, a spindle slidably and rotatably mounted in said spindle support, a cylinder carried by said spindle support in axial alignment with said spindle, a piston slidably mounted 50 in said cylinder, a thrust bearing connecting said piston and said spindle, and means for selectively introducing pressure into said cylinder to move said spindle toward said work support.
- 55 2. In a device of the character described a plurality of lens grinding mechanisms, each mechanism comprising a support, a spindle rotatably mounted in said support, a second support, a second spindle rotatably and slidably mounted 55 in said second support, in substantial alignment with said first spindle, means on one spindle for holding a lens, means on the other spindle for holding an abrading tool, means for rotating one spindle of each mechanism, intermittent means for sliding the slidable spindle of each mechanism toward and from its cooperating spindle, a lens handling device for moving the lens from one grinding mechanism to the next, and a timing mechanism for operating said intermittent 70 means and said lens handling device.

3. In an apparatus of the character described a plurality of lens grinding mechanisms, each mechanism comprising a pair of aligned rotatable spindles, one of which is axially movable, means for moving said spindle axially, means on one spindle for holding a lens and means on the other spindle for holding an abrading tool, means for moving a lens from one grinding mechanism to the next, a continuous drive means for rotating one spindle of each mechanism, an intermittent mechanism driven from said continuous drive means and means for interconnecting the lens moving means and the means for axially moving said spindles to said intermittent means.

4. In a lens grinding machine a plurality of lens grinding mechanisms, each mechanism comprising two spindles rotatably mounted in substantially axial alignment, means on one spindle of each mechanism for holding a lens, means on the other spindle for holding an abrading tool, one spindle of each mechanism being substantially axially movable, a rotatable cam shaft, a cam on said shaft for each movable spindle for moving said spindle axially, a lens shifting device, cylinder and piston means for actuating said lens shifting device to shift a lens from one grinding mechanism to the next, a source of compressed fluid connected to said cylinder and piston means, valves for controlling the flow of said fluid to said cylinder and piston means, motor means for rotating one spindle of each grinding mechanism, a timing device, means for operating said timing device from said motor means and means for operating said cam shaft and said valves intermittently from said timing device.

5. In a lens grinding machine a plurality of lens grinding mechanisms, each mechanism comprising two spindles rotatably mounted in substantially axial alignment, means on one spindle of each mechanism for holding a lens, means on the other spindle for holding an abrading tool, one spindle of each mechanism being substantially axially movable, a rotatable cam shaft, a cam on said cam shaft for each movable spindle for moving said spindle axially, a lens shifting device, cylinder and piston means for actuating said lens shifting device to shift a lens from one grinding mechanism to the next, a source of compressed air, valves for controlling the flow of said compressed air to said cylinder and piston means, operative interconnections for controlling said valves from said cam shaft, a motor for driving one spindle of each mechanism, a shaft driven by said motor, a driving connection between said motor and said cam shaft, a clutch in said driving connection, means for causing disengagement of said clutch and means for causing reengagement of said clutch.

6. In a lens grinding machine, a support, a spindle freely rotatable in said support, a grinding lap eccentrically mounted on one end of said spindle, a second support, a second spindle rotatably mounted in said second support in opposed relation to the first-named spindle, a lens carrying support mounted on said second spindle for holding a lens against said lap and means for driving said second spindle.
